TOY PARACHUTE

Carl W. Larson, Aurora, Colo.

Application March 10, 1958, Serial No. 720,232

6 Claims. (Cl. 244—155)

This invention relates broadly to the class of toys and more particularly to a toy parachute for use in connection with a kite.

While numerous attempts have been made to provide a toy novelty in the form of a parachute adapted to ride up the anchor line or string of a kite and be disengaged therefrom at a predetermined elevation, none of these attempts, so far as is known, have been completely successful in providing a virtually foolproof mechanism of release which will operate unfailingly in the hands of a child as the ultimate user.

It is an object of this invention, therefore, to provide an improved toy parachute and releasing device which avoids one or more of the disadvantages of the prior art arrangements and is virtually foolproof.

It is a further important object of this invention to provide an improved toy parachute carrier and release device which will automatically release the parachute at a predetermined elevation.

A further object of the invention is to provide an improved toy parachute and release device which is simple and inexpensive to manufacture yet ruggedly constructed to withstand frequent and repeated use.

A still further object of the invention is to provide an improved toy parachute and release device which will automatically release the parachute at a predetermined point along the kite string regardless of the lack of care with which the parachute is positioned on the kite string.

In accordance with the invention, the toy parachute and release device are to be used together in association with a kite and kite string and are seen to comprise a toy parachute having guide means connected to the shroud lines at the apex thereof adapted to operatively engage the kite string in a secured movable relationship along the length thereof, together with release means adapted to be connected into the kite string and to automatically disengage the guide means from the kite string at a predetermined point.

For a better understanding of the present invention, together with other and further objects thereof, reference is had to the following description taken in connection with the accompanying drawings and its scope will be pointed out in the appended claims.

In the drawings:

Figure 1 is a perspective view illustrating the application of the present invention to a kite string;

Figure 2 is a view in elevation of the parachute of the invention with parts broken away to conserve space;

Figure 3 is a side elevation of a portion of the parachute of Figure 2 showing the guide means;

Figure 4 is a view taken along line 4—4 of Figure 2;

Figure 5 is an enlarged elevation of the release means of Figure 1 showing the relative positioning of the guide means with the release means in dotted lines at the point of release;

Figure 6 is a side elevation of the guide means and release means at the point of release;

2

Figure 7 is a plan view of one form of release means as shown in Figures 5 and 6;

Figure 8 is a plan view of another form of the release means;

Figure 9 is an elevation of the release means of Figure 8;

Figure 10 is a side elevation, partly in section, taken along line 10—10 of Figure 9; and

Figure 11 is a side elevation partly in section, of another form of the release means according to this invention.

Referring to Figure 1, it will be seen that the present invention comprises two units which are to be used in connection with a kite and kite string of any suitable

form. These two units are generally identified by letters P and R and comprise respectively a toy parachute constructed of any suitable light weight material such as light paper, cloth or plastic and a release device which is connected into the kite string and preferably located

therein in the immediate vicinity of the kite. It is seen in Figure 1 how the units are combined for use with kite 20 and kite string 22. The kite string 22 is separated as at 23 and release means R is inserted into the line as by securing each end of the separated string 22 to re-

lease means R. As seen in Figure 7, the release means is comprised in one form of a flat plate 24 of a semi-rigid material, such as plastic and the like, which may conveniently be in the shape of a rectangle. A pair of holes 26 are provided in diagonally opposite corners of the plate.

A rod 28 of lesser diameter than holes 26 is positioned within each of the holes and movably secured against escape therefrom. As seen in Figure 6 rods 28

may conveniently comprise a cotter pin and the like provided with a string receiving loop 30 at one end there-

of with the other end spread to prevent escape of the rods from the holes. In use the ends of the separated kite string are attached to rods 28 as by passing through loops 30 and tying securely.

Referring now to Figures 2 and 3, the parachute P is seen to be comprised of a canopy 32 of a light weight material, such as silk, paper, plastic or the like. A plurality of shroud lines 34, which may conveniently be in the form of semi-rigid plastic rods, are secured at one

end thereof to canopy 32 at spaced points around the periphery thereof by suitable means such as by gluing and the like, as shown at 36 in Figure 4. The other ends of shrouds 34 are each seen to be passed through holes 38 in each corner of a plate 40 of plastic or the like.

Fasteners 42 are frictionally secured to the ends of shrouds 34 to prevent withdrawal thereof from holes 38. A centrally positioned hole 44 is provided in plate 40.

A guide element 41 is supported by plate 40 and is seen to comprise a wire 46 having one end passing through hole 44 in plate 40 and secured by means of a washer 48 and a flattened portion 50 on the end of wire 46.

The other end of wire 46 is bent at right angles to form a stub shaft having thereon a V-groove pulley 52 mounted for rotation and secured against escape by washer 54 and flattened portion 56 at the other end of wire 46.

Wire 46 is preferably provided with additional bends as at 58 and 60 such that the V of pulley 52 is aligned with the portion of wire 46 passing through hole 44 of plate 40.

The release device R in use is placed in the kite string 22 near the kite so that when the kite is flying, the parachute P will be caused to rise on the string to a substantial elevation before it is released for descent in open condition. Parachute P is suspended on the kite string

22 by means of pulley 52 of the guide device 41. The parachute may be placed on the string from either side and still be released in a satisfactory manner as will be described hereinafter. The shrouds 34 being of a semi-

3

rigid plastic prevent entanglement even in the hands of small children. The parachute will be moved up the kite string guided by pulley 52 by the action of a breeze on canopy 32, Figure 1. When release device R is reached, pulley 52 rides onto plate 24 over down-string rod 28, Figure 5. The presence and weight of the parachute causes release R to tip, releasing parachute P from the kite string for descent in open condition, Figure 6. Since plate 24 may tip to either side of the string, it is immaterial whether wire 46 of guide element 41 is placed on one side of string 22 or the other. In either placement, a positive releasing action of the parachute is achieved. It is to be noted that the central portion of release means R is of a width greater than the top of the V-groove of pulley 52 to effect positive release thereof.

The release device R may also be shaped of metal or a thermo-plastic in a manner shown in Figures 8, 9 and 10. Another form is shown by Figure 11. The release device of these figures is seen to comprise a plate 62 having a central V-bend 64 with each leg of the V having outwardly projecting ears 66 provided with holes 68 for attachment of kite string 22. Ears 66 may conveniently be provided with a convex upper surface to facilitate movement of pulley 52 thereover. The release device of Figure 11 is similar in shape, but with the ears pinched as at 70 and provided with horizontal holes 72 for receiving string 22.

Although the above-described embodiments disclose the invention as applied to a parachute, it is to be understood that the invention may also be employed in connection with other flying type toys which present sufficient surface area to be propelled up a kite string by the available breeze. Such toys may be in the form of toy gliders and the like.

While there has been described what at present is considered to be the preferred embodiment of this invention, it will be obvious to those skilled in the art that various changes and modifications may be made therein without departing from the invention. It is aimed therefore in the appended claims to cover all such changes and modifications which fall within the true spirit and scope of the invention.

What is claimed is:

1. A toy comprising in combination: a parachute, guide means depending therefrom adapted to engage a kite string and release means adapted to be connected thereto in depending relation to effect disengagement of the guide means and attached parachute from the string comprising a generally V-shaped member with upwardly extending legs thereof adapted to be attached into the kite string and a central portion of substantial width as compared with the width of the guide means depending from the legs and positioned sufficiently below the string to locate the center of gravity of said release means substantially below a string connected thereto.

2. A combination as set forth in claim 1 wherein the

guide means comprises a V-groove pulley and the central portion of the generally V-shaped release means is of a width greater than the width of the top of the V-groove of said pulley.

3. A combination as set forth in claim 1 wherein the release means is comprised of a flat rectangular central portion having a pair of upwardly extending rods attached at diagonally opposed corners thereof and flared outwardly from the corners forming a generally V-shaped structure and said rods being provided with means remote of the flat portion adapted to receive and secure an end of the kite string.

4. A combination as set forth in claim 1 wherein the release means is comprised of an elongated sheet of a material adapted to be shaped, shaped in a V-shape with the legs thereof having an outwardly projecting ear and each ear is provided with an opening therein adapted to receive and secure an end of the kite string.

5. As a new article of manufacture, a release device for releasing toys from a kite string comprising a flat rectangular plate having a pair of upwardly extending rods attached at diagonally opposite corners and flared outwardly from the corners to form a generally V-shaped structure with each of said rods being provided with means remote of said plate adapted to receive and secure an end of a kite string, the plate being positioned sufficiently below the string receiving means to locate the center of gravity of said release means substantially below a string connected thereto.

6. A toy comprising in combination, a parachute having a canopy, a plurality of semi-rigid shroud lines attached at one end thereto, a rectangular plate with the other end of the shroud lines connected to the corners of the rectangular plate and guide means depending centrally from said plate comprising a V-groove pulley mounted for rotation about an axis normal to said plate and adapted to operatively engage a kite string in a secured movable relation along the length thereof and release means adapted to be connected into the kite string to automatically disengage the guide means from the kite string at a predetermined point comprising a flat rectangular plate having a pair of upwardly extending rods attached at diagonally opposite corners and flared outwardly from the corners to form a generally V-shaped structure with each of said rods being provided with means remote of said plate adapted to receive and secure an end of a kite string, the plate being positioned sufficiently below the string receiving means to locate the center of gravity of said release means substantially below a string connected thereto.
